(57) CLAIM

I claim the ornamental design for an display screen with icon or packaging with surface ornamentation, as shown and described.

DESCRIPTION

FIG. 1 is a front view of an display screen with icon or packaging with surface ornamentation in accordance with a first embodiment of my new design;

FIG. 2 is a front view thereof in accordance with a second embodiment of my new design; and,

FIG. 3 is a front view thereof in accordance with a third embodiment of my new design.

The broken line showing the display screen or packaging is included to illustrate environmental features and forms no part of the claimed design.
